CARL OSCAR CLÉMENTZ, OF MALMO, SWEDEN

COMBINED PERMUTATION AND SNAP ACTION LOCK

Application filed January 4, 1926, Serial No. 79,215, and in Sweden February 9, 1925.

This invention relates to a permutation and snap-action lock combined in a special manner, offering several advantages when using same as well as from the manufacturing point of view.

5 The inner parts of the lock constituting the distinguishing parts of a permutation lock may be said to generally consist of a permutation-controlled lock-bolt and permutation elements, which latter may be of various kinds, but are usually made up of circular discs rotatable about their own axes and in their own plane, each disc being provided with a recess, whereby a sliding or any other movement of the said lock-bolt is rendered possible, as soon as the permutation elements, with their recesses hidden within the lock, are set to occupy a predetermined position in relation to the said lock-bolt, that is to say, as soon as they are set in a correct ("combination") position.

The chief object of the present invention is to provide a receptacle for the lock so constructed, that the lock or a division thereof may be taken to pieces without utilizing any other auxiliary means than for instance a match, a pin or the like, after correctly setting the permutation elements and after sufficiently displacing the permutation-controlled lock-bolt or other members dependent thereupon, whereby an aperture is uncovered, through which the said auxiliary means, such as a match, is inserted with appropriate pressure, so that a retaining or locking device is moved out of action, whereupon the receptacle or a division thereof may be taken to pieces or removed, so that the inner parts become accessible and may be taken out for certain purposes, for instance for exchanging the permutation elements.

40 As it is immaterial for the correct conception of the invention on the whole what kind of permutation elements are used I have, for the sake of simplifying the following specification and the accompanying drawings chosen such elements which consist of substantially circular discs.

The arrow signs in the various figures on the drawings designate the direction of the pressure of the various springs and as well

the direction of movement of the parts being caused and conditioned by said spring pressure.

Referring to the drawings Figs. 1 and 3 are elevations of the permutation elements and Fig. 2 is a vertical section through these elements assembled together. Fig. 4 is an elevation of the receptacle for the lock with some lock parts mounted therein, the cover being removed. Fig. 5 is a side elevation of same and Fig. 6 shows a vertical section of same on the line 6—6 in Fig. 4. Fig. 7 is a plan of the cover of the lock and Fig. 8 shows the same in a lateral view. Fig. 9 is a horizontal section representing the receptacle with lock parts mounted therein on the line 9—9 in Fig. 5 and Fig. 10 shows the catch plate with the catches shown in elevation, adapted to cooperate with the parts shown in Fig. 9. Fig. 11 shows a modification of the receptacle for the lock with lock parts inserted therein in a horizontal section on the line 11—11 in Fig. 12 and Fig. 12 shows this modification in a transversal section with the inner lock parts removed. Fig. 13 is a vertical section of the catch plate with the catch in elevation adapted to cooperate with the lock parts shown in Fig. 11. Fig. 14 shows on a larger scale a fragmental view of the parts included in the modification shown in Figs. 11 and 12. Fig. 15 shows the assembled permutation elements for use in connection with the modification shown in Figs. 11 and 12. Fig. 16 shows another modification of the receptacle for the lock with permutation elements inserted therein. Fig. 17 shows the same in a longitudinal section and Fig. 18 shows the same in a transversal section along the line 18—18 in Fig. 16. Fig. 19 shows still another modification of the lock parts in a lock receptacle partly in a horizontal section and Fig. 20 is a longitudinal section of the member adapted to cooperate with the lock-catches shown in Fig. 19. Fig. 21 represents a horizontal section of a further modification of the lock parts in a lock receptacle partly in elevation and Fig. 22 is plan of the member adapted to cooperate with the lock-catches or hooks shown in Fig. 21, the catch pins being shown in section.

45 50 55 60 65 70 75 80 85 90 95 100

According to Fig. 1 the permutation member consists of two assembled elements, of which the one Y in the form of a disc is partly accessible from the exterior of the receptacle and provided with permutation signs, such as numbers, letters or the like, and further provided with minor holes 1. The middle portion of this disc Y is pressed down to form the cup like part 2. The other element consists of a substantially circular disc I provided with a radial slot 3 and smaller circumferential recesses 4 and also with minor holes 5. Both discs Y and I have a bore hole in the center serving as a journal 15 for a stud. The permutation signs on the disc Y consist of one hundred angular units marked in Fig. 1 as 0, 10, 20 and so on. The ten holes 1 in the disc Y are arranged in a circle spaced at equi-distances each distance 20 corresponding to ten angular units and the ten holes 5 in the disc I also arranged in a circle with the same radius as that of the first named circle are spaced at equi-distances each distance corresponding to nine angular 25 units. The discs Y and I may be held together in a relative position by means of a bent pin 6 the one end of which is inserted through a hole 1 of the disc Y and a hole 5 of the disc I, and it will be clear that on 30 account of the different spacing of said holes 1 and 5 a relative position of the two discs Y and I may be obtained in one hundred variations.

Amongst other objects of the invention one 35 object however is to provide another axial fixing means, than that just described. Referring to Figs. 4 and 5 the two permutation elements are rotatable about studs 7 securely fixed to the bottom of the receptacle 8 by 40 riveting, and the permutation-controlled lock-bolt 9 having perpendicularly extending projections 10 and 11 is fitted adjacent the bottom of the receptacle underneath the permutation elements. Further a rocking lever 45 12 is pivotally mounted on the stud 13 on the one short side wall of the receptacle 8. After the permutation elements are correctly set their slots 3 register with the projections 10, 10 and after longitudinally displacing the 50 permutation lock-bolt 9 the said projections enter the slots 3, at the same time as a hole 14 in the one long side wall of the receptacle is uncovered, which hole is covered by the projection 11 on the lock-bolt 9, when this is in 55 locked or locking position. The lid or cover 15 (Fig. 8), three edges of which are bent down and inwards, can be pushed on the receptacle 8 from its one end only. The long walls of the receptacle are provided with 60 outwardly extending guiding members 16 which are engaged in gripping relation by the bent edges of the cover 15. When the cover is pushed on the receptacle in its place the free end of the flat spring 17 fastened to 65 the cover rests upon the lever 12 and abuts

the inside of the short wall of the receptacle 8, whereby the cover is prevented from being removed. The cover may however be removed after the permutation elements have been correctly set and the permutation lock-bolt has been displaced so that the hole 14 becomes uncovered, through which hole an appropriate tool is inserted under the lever 12 which thereby is forced up and thus presses the end of the flat spring 17 over the edge of the short wall of the receptacle, so that the cover may be withdrawn. The cover is provided with apertures 18 for reading off the signs or marks on the permutation elements. When the cover 15 is in its pushed-in position the permutation elements are kept together axially between the bottom of the receptacle and the cover, the circles shown with dotted lines in Fig. 7 showing the position of the permutation elements Y under the cover, and it will be observed that they laterally protrude sufficiently so as to be accessible from the outside for setting the same into "combination" position. The recesses 4 in the circumference of the element I only serve the 90 purpose to guard against the discovery of the slot 3 by touch feeling.

Fig. 9 shows in what manner the inner parts of the lock underneath the permutation elements are arranged. These parts operate as follows:—After the permutation elements are correctly set the permutation lock-bolt 9 and the snap-action lock-bolt 19 are manually pressed towards each other, when a third bolt member 20 will be caused by said bolt 9 to partake in the movement of the latter. By this action the opening 21 between the bolt 19 and bolt member 20 will be enlarged. The studs or catches 23 having annular grooves 22 are fixed to a catch plate 24 and adapted to be inserted through corresponding apertures in the bottom of the receptacle and to cooperate with and be locked by the bolt 19 and bolt member 20. The catch plate 24 is, of course, attached to the member desired to be locked in cooperation with the lock described; that is, for instance, the lock proper will be positioned on the flap of a portfolio and the catch plate 24 on the portfolio itself. When the opening 21 is enlarged as aforesaid the catches 23 are disengaged and may be withdrawn. When the manual pressure on the bolts 9 and 19 ceases they return by the action of a spring π to their initial position, but the bolt member 20 does not return because it is locked in its inoperative position by means of a flat spring catch 25, which falls with its free end into a notch 26 in the bolt member 20. The lock functions now, irrespective of the position of the permutation elements, as a snap or spring lock. That is to say, when under any permutation operation the bolt member 20 has been moved to a position, which in correspondence with the manually operative posi- 125 130 135

tion of the bolt 19, permits withdrawal of the catches 23, such bolt member 20 is retained in this position by the spring 25 engaging in the notch 26 of such bolt member. Then the control of the locking engagement of the catches 23, or their release, is entirely within the operative movement of the bolt 19, so that by manually moving this bolt member, which is wholly free of the permutation elements, the catches 23 may be released, or after insertion of such catches, the normal spring influenced position of the bolt 19 serves to hold the catches. As the bolt 19 is arranged for free manual operation, it is apparent that the lock in the described position of the parts, is a snap or spring lock operating wholly independent of the permutation elements. When the spring catch 25 however is withdrawn by a knob accessible from the exterior of the receptacle out of engagement with the notch 26 the bolt member 20 returns by the pressure of a spring into operative position as shown in the drawings (Fig. 9) and the lock can now only be used as a permutation lock.

According to Fig. 9 the bottom of the receptacle 8 is provided with a hole 14a covered by the bolt 9 when in operative position, and when this bolt is in inoperative position the hole 14a registers with a corresponding hole 14b in the bolt 9. These holes 14a and 14b serving the same purpose as the hole 14 in Fig. 6 an appropriate tool may be inserted therethrough for lifting the flat springs 17 on the cover out of its operative position and thus enable the cover to be removed. According to the mode of adaptation the one or the other of the two described arrangements, that is either the hole 14 or the two holes 14a and 14b may be applied.

Figures 11 to 14 show a modification of the lock shown in Figures 1 to 10. In this modification the permutation elements (Y I) are rotatably mounted on a central cup 27 which is shown in section in Fig. 11 and which adjacent the bottom of the receptacle has the form of, for instance, three peripherically positioned hooks 28, as illustrated in Fig. 14, which hooks cooperate with loops 29 fixed to the bottom of the receptacle 30 which also has the form of a cup. The inner cup 27 may be released from engagement with the loops 29 and thus from the outer cup 30 by rotating the same to the left (counter-clockwise), provided the permutation lock-bolt has previously been pressed in, so that the slot 31 thereon registers with the circumference of the inner cup 27, and provided the flat spring 32 protruding with a vertical projection through an aperture in the bottom of the outer cup or receptacle 30 has been sufficiently drawn out. In Fig. 12 the permutation elements, Y, I, while being shown as preferably of integral construction, may consist of two parts. For instance, as shown in

Fig. 15, they may consist of two coaxially disposed annular discs Y' and I', which are adapted to be positioned in different angular positions in relation to each other, the inner annular disc or ring I' being provided with a slot 3 and recesses 4 in the same manner as the disc I shown in Fig. 1. The purpose intended with the recesses is accomplished in the most preferred manner by giving the same and the adjacent portions of the circumference a continuous wave form, the slot 3 being arranged in the middle of a cavity. In this modification the permutation lock-bolt 9 is provided with one projection 10 only which extends perpendicularly to the surface of the bolt up to the level of the uppermost permutation element. The spring 19' and 20' fixed to the receptacle 30 are adapted to successively cooperate with the catch 33 (Fig. 13) when this is inserted through the corresponding aperture 34 in the bottom of the receptacle. The catch or stud 33 is provided with straight cuts or grooves 35 and 36 of different widths and when pushing the catch into the lock the spring 19' will first snap into the cut 35 and afterwards the spring 20' drops into the cut 36. The catch or stud 33 is provided at its base with threads onto which is screwed a nut 37. By somewhat unscrewing the nut the catch or stud cannot be inserted in the aperture to its full length and therefore the spring 20' cannot be operative. For the sake of clearness the inner lock parts shown in Fig. 11 have been omitted in Fig. 12.

Figs. 16, 17 and 18 show the receptacle 8 in a third modification with the cover 15 in its proper place, the permutation elements Y² and I² being arranged on studs 7 fixed to the bottom of the receptacle 8 by riveting. The cover 15 has its two long sides bent down at right angles in relation to its plane and is placed on the receptacle 8 in such a manner that the one short side having in cross section the form of a hook 38 grips about a projection 39 extending from the upper edge of the one short wall of the receptacle 8 (Fig. 17), while the other short side of the cover being bent down and provided with hooks 40 in the plane of the bend engages corresponding hooks 41 on the locking member 12 (Fig. 18). Through a hole 14 in the receptacle 8, being covered or uncovered in a similar manner as shown in Fig. 4 by the permutation lock-bolt, an appropriate tool may be inserted for releasing the hooks 40 from engagement with the hooks 41 of the locking member 12.

While Figures 9 and 11 individually show a lock having one permutation lock-bolt 9 and two snap-action lock-bolts, as 19 and 20, Fig. 9, or two equivalent springs 19' and 20' of Fig. 11 the modification shown in Fig. 19 shows a lock having one permutation lock-bolt 9, but only one snap-action lock-bolt 19.

The mode of operation of this modification is the following:—After correctly setting the permutation elements the permutation lock-bolts is operated against the pressure of a spring by means of a double armed rocking lever 43 pivotally mounted on the stud 42. Hereby the permutation lock-bolt 9 presses against the one end of a pivotally mounted double armed lever 44, the other end of which has the form of a hook so that the latter, which 5 when operative grips behind the one arm of a bell crank lever 45, releases this lever and allows the same to move into such position, that the permutation lock-bolt 9, irrespective of the setting of the permutation elements, 10 may be shifted by means of the rocking lever 43 which contacts with a pin 46 on the bolt 9 and also with a pin 47 on the bolt 19. Thus, when the bell crank lever 45 is in inoperative 15 position the lock may be used as a snap or spring lock and is converted into a permutation lock when pressing the bell crank lever 45 by means of the knob 43 accessible from the outside of the receptacle into operative 20 position, that is the position shown in Fig. 19. 25 Figs. 21 and 22 show a lock having one lock-bolt member 9 only which serves both as permutation lock-bolt and as snap-action lock-bolt because of the fact that it is adapted to move in two directions. This modification acts as follows:—After correctly setting the permutation elements the permutation lock-bolt member 9 is pushed to left against the pressure of the spring acting on the member 49, whereby the member 49 partakes in 30 this movement. The one end of the pivotally mounted spring actuated double armed lever 50 falls by the aforesaid movement behind the abutment 51 on the member 49, whereby the locking action of the lever 50 on the lock-bolt member 9 is relieved and the member 49 35 is kept inoperative, so that the latter cannot follow the return movement of the lock-bolt member 9. In consequence this latter may be 40 displaced in the opposite direction beyond its initial position and thus functions as a snap or spring lock, irrespective of the setting of the permutation elements. By pressing the knob 52 inwards the lever 50 and the member 49 are caused to occupy their operative position 45 as shown in Fig. 21. If the lock-bolt member 9 is divided along the dotted line the part having catch hooks 53 need not partake in the first named movement of the lock-bolt member, so that the catch hooks 53 may be 50 provided with a more favourable form than that shown in the drawings.

In certain modifications for practical use it may be preferred to mount the permutation elements only and in some cases also the permutation lock-bolt within a room or department of the receptacle adapted to be taken to pieces in the manner described above.

With regard to the modification shown in 55 Fig. 19 it should be obvious that instead of

the snap-action lock-bolt 19 the rocking lever 43 may be locked and unlocked respectively by a device in analogy with the locking device 45, 48 shown in Fig. 19 or 49, 50 shown in Fig. 21. In such case the lock may function in a manner similar to that shown in Fig. 9 and Fig. 21 (if the permutation lock-bolt is divided along the dotted line), by simply pressing together the two main parts of the lock.

As already disclosed in the specification and the drawings the invention may be carried out in a great number of various modifications.

What I claim and desire to secure by Letters Patent is:—

1. A permutation lock comprising in combination a receptacle, permutation elements, a permutation-controlled lock-bolt, a snap-action lock-bolt, a third bolt member adapted to be moved into inoperative position by said permutation-controlled lock-bolt, means for retaining said third bolt member in inoperative position, so that the snap-action lock-bolt alone may act as bolt-ing member independent of the setting of the permutation elements, means for releasing said third bolt member retaining means, a detachable cover and releasable retaining means for keeping the cover in its place.

2. A permutation lock comprising in combination a receptacle, a detachable cover, releasable retaining means for keeping the cover in its place, permutation elements consisting of two discs each disc provided with holes arranged in a circle and equidistantly spaced but differently on each disc, the discs arranged to be set in different relative angular positions, a pin cooperating with registering holes in the two discs to maintain their relative positions, and locking members, the movement of one of said members depending upon the setting of the permutation elements.

3. A permutation lock including a locking casing adapted to be secured to one part of the receptacle to be locked, a catch element to be secured to the other part of the receptacle to be locked, means within the casing, permutation members controlling the movement of the means, and an automatically operable member cooperating with said means following permutation release operation thereof to hold the means for service as a snap action lock for the catch wholly independent of the position of the permutation members, said automatically operable member being manually controlled to permit said means to be returned to the governing influence of the permutation members at will.

In testimony whereof, I have signed my name to this specification.

CARL OSCAR CLÉMENTZ.
